(57) **CLAIM**

The ornamental design for a school bag hanging system, as shown and described.

DESCRIPTION

FIG. 1 is a perspective view of the school bag hanging system;

FIG. 2 is a right side elevational view thereof shown enlarged, it being noted that the left side elevational view is a mirror image of the right side elevational view;

FIG. 3 is a front elevational view thereof;

FIG. 4 is a sectional view thereof as taken along line 4-4 of FIG. 3 shown enlarged;

FIG. 5 is a top plan view thereof;

FIG. 6 is a bottom plan view thereof; and,

FIG. 7 is a rear elevational view thereof.

The broken lines represent environment only and form no part of the claim. The boundary lines represent a boundary of the claim.
